UNITED STATES PATENT OFFICE.

WILLIAM F. CATHCART, OF CHICAGO, ILLINOIS.

HYDROCARBON GENERATOR AND BURNER.

1,210,597.

Specification of Letters Patent. Patented Jan. 2, 1917.

Application filed February 18, 1915. Serial No. 9,013.

To all whom it may concern:

Be it known that I, WILLIAM F. CATHCART, a citizen of the United States, residing at Chicago, in the county of Cook and State of Illinois, have invented certain new and useful Improvements in Hydrocarbon Generators and Burners, of which the following is a specification.

My invention relates to improvements in generators and burners for hydro-carbon liquid fuels.

One of the objects of my invention is to provide a new and useful combined generator and burner whereby the highest efficiency may be effected in the conversion of a liquid fuel into a highly combustible fluid, vapor or gas, subsequently to be consumed or converted into heat at the burner of the device.

Another object of my invention is to generally improve devices of this character to enhance their efficiency and to cheapen their construction.

Other and further objects of my invention will become readily apparent to persons skilled in the art from a consideration of the following description when taken in conjunction with the drawings wherein:

Figure 1 is a plan view of an organization showing my invention; Fig. 2 is a longitudinal section, taken on line 2—2 of Fig. 1. Fig. 3 is an enlarged detail of an automatic fuel controlling device or shut off. Fig. 4 is a section taken on line 4—4 of Fig. 1. Fig. 5 is a section taken on line 5—5 of Fig. 4. Fig. 6 is a section taken on line 6—6 of Fig. 5. Fig. 7 is a section taken on line 7—7 of Fig. 1. Fig. 8 is a section taken on line 8—8 of Fig. 1. Fig. 9 is a section taken on line 9—9 of Fig. 1. Fig. 10 is an end view of a regulable cold air admission register. Fig. 11 is a plan view of means for inserting a suitable detergent into the generator and burner to purge it of accumulations or deposits that may result from distillation of the liquid fuel.

In all the views the same reference characters are employed to indicate similar parts.

I will now describe a typical embodiment of my invention so that persons versed in the art may know how to make and use the same.

The liqued fuel, to be used in connection with my generator-burner is to be contained in a pressure tank 12, pumped thereinto by means of a suitable pump 13, and a supply

pipe 14, and taken therefrom by the pipe 15, shown in dotted lines descending to a point near the bottom of the tank. After sufficient oil, or other liquid fuel has been pumped into the tank 12, connection from the nipple 16 of the pump 13 to the oil supply may be broken and air may be pumped upon the top of the oil in the tank 12, until the desired pressure within the tank is registered upon the pressure gage 17. Valves 18 and 19 control the contents of the tank. A pipe 20 leads from the valve 18 through a check-valve connection 21, to be hereinafter more fully explained, through a controller or automatic cut off 22 into a valve structure 23. This needle valve structure 23, is more clearly shown in Fig. 8. The fuel liquid comes through the pipe 20 into the chamber 24, which is controlled by the needle 25 of the valve, adapted to be turned by means of the knurled head 26, so as to open and control the valve to admit the liquid into the strainer 27. The strainer consists of a tube having a screen 28 and 29 at its respective ends and filled between these foraminous disks with a material such as asbestos wool 30, or the like, the object being by the use of this device, to cleanse the liquid of any mechanical obstructions that it may contain before admitting it into the generator pipe 31. From the strainer 27 the liquid fuel passes through the pipe 31, which is folded upon itself, and shown in dotted lines, as at 31, and out from the pipe 31 into the needle valve structure 32, and is controlled by the needle valve 33 operable by the knurled head 34. At the base of the point 35 of the needle valve proper is a shoulder 36, which is adapted to be seated upon a shoulder 37 of the port 38. This permits seating of the valve and closing it tightly without the necessity of imposing unnecessary pressure or tension upon the point 35 and the walls surrounding the port 38.

The casing 33', within which the pipe 31 is contained, is more clearly shown in Figs. 5 and 6 wherein 34' is a box of suitable material, such as sheet metal, containing a burner pipe 35' and a top or cover 36', spaced apart from the body part of the box, as at 37', and held in spaced relation by the braces 38'-38'. To hold the heat within the casing and to protect the cover 36' from excessive heat generated by the burner 35' I prefer to line the cover with a sheet of

asbestos or other similar insulating material 39. The ejecting orifices of the burner 35' are contained in a horizontal plane and substantially midway between the body portion 34' and the cover 36' of the casing, so that a sufficient amount of air is admitted to the burner, through the space between the body part 34' and the cover 36', to support combustion. The lining 39 and the cup shape of the cover 36' form a canopy which serves to hold the heat in close relation with the generating pipe 31. The burner 35' is held in place in the body part 34' of the casing, by means of bands 40—40 that surround the tube of the burner and are connected to the body portion 34' of the box as by rivets 41. By this means a large surface of the generating pipe 31 is directly exposed to the flame that issues from the burner 35'. The liquid that is permitted to pass through the strainer 27 is converted into a vapor or gas, in the pipe 31 and given considerable velocity by the effect of the heat from the burner 35', which gas passes from the pipe 31 into and through a needle valve 32 and is expanded into a mixing chamber 42, consisting of a T 43 in which is screwed a reducing plug 44 and into which plug is screwed a protecting pipe or tube 45, and into the latter is placed a vapor tube 46, terminating, as at 47, near the needle valve point 35 and port 38. The other end of the tube 45 enters an expansion fitting 49, the vapor tube passing well into this fitting and terminating as at 50. The vapor tube is provided with a series of notches or slots 51 which terminate some distance from the end 52 of the tube 45, for a reason to be more fully hereinafter explained.

40 A reducer fitting 54 is screwed into the vertical end of the T 43, and into the reducer plug 54 is screwed a pipe 55 which is doubled upon itself, by parts consisting of the elbow 56, the section 57, the half circle fitting, or double elbow 58, and the pipe section 59 which latter pipe extends forwardly and terminates in an enlarged screened cap 60, provided with an air screen 61. The pipes 57 and 59 are extended back into the region of the burner 50 or a zone heated thereby so as to heat the air that comes in through the pipe 59, the fitting 58, the pipe 57, the elbow 56 and pipe 55 and through the mixing chamber 42. Hot air will come through this system of fittings 55 and pipes into the mixing chamber 42 and will mix with the gas or vapor coming through the needle valve 32 and will be driven into the vapor tube 46 and then into the secondary mixing chamber 62 provided by the enlarged pipe 63. An elbow 64 is screwed into the other vertical end of the T 43 and into this elbow is screwed a short section of pipe 65 which terminates in an enlarged cap 66, having a regulable register 67 in its open end. The register 67 is pro-

vided with a handle 68 whereby to vary the size of the openings 69—69 to admit a greater or less quantity of cold air into the pipe 65, and from thence into the mixing chamber 42. Thus it will be seen that hot air will enter through the pipe 55 into the mixing chamber 42 and a regulable quantity of relatively cold air will pass through the pipe 65, the elbow 64, into said chamber, thereby providing means for regulating the quantity of air to be mixed with the vapor or gases to be passed into the vapor tube 46 and into the secondary mixing chamber 62. The gas and air will pass through the vapor tube 46 with considerable rapidity and will be mixed to some extent in said tube, but they will pass out of the end of the tube, as at 50, thereby producing more or less of a back current or whirl between the slotted end section of tube 46 and the walls of the expander 49, as at 70, thereby causing some of the air and mixed vapor to pass inwardly through the slots and be entrained with the vapor flowing through tube 46, assisting in effecting the desired mixture of air and fuel. Of course the slots or openings 51 are not entirely essential to the operation of my generator and burner, but they do, to a greater or less extent, produce a whirling of the air and vapor thereby causing a better and more thorough admixture of these gases. I may provide an additional mechanical means for assisting in mixing the air and vapor, in the chamber 62, consisting of a spinner 71 mounted on a stud 72 fixed to a cross bracket 73 that is secured in the tube 63. The side wings 74 and 75 of the spinner, are oblique so that the impingement thereon of the gases and air, coming through the tube 46, striking the oblique sides of the spinner as they are projected into the secondary mixing chamber 62, causes a violent rotation of the spinner and mechanical agitation of the fuel mixture. The admixed fuel in the mixing chamber 62 passes from the tube affording the walls for said chamber, 63, into the semi-circular fitting 76, and from thence into a burner 77. The flame issuing from the burner 77, while capable of utilization as a part of the general heating capacity of the burner device, also, being placed immediately below the secondary mixing chamber casing 63, heats the gases contained in said mixing chamber and thereby causes more thorough admixture of the air and gases therein contained.

Other burners, and any desired number thereof may be supplied from the mixing chamber 62, as for instance I have shown a fitting 78 connected to the end of the burner 77 to which is screwed a pipe or nipple 79 and to the nipple 79 is screwed a T 80, from which is taken a pipe 81 to supply the burner 35' and from which is taken another pipe 82 to supply the burners 83 and 84. A re-

130

ducer 85 may be screwed into the end of the T 80 and into the reducer a smaller pipe 86 may be taken to supply the burners 87 and 88 and thus even a larger number of burners, 5 than those shown, may be employed and connected in the same manner with the mixing chamber of the generator.

In order to provide for shutting off the gas or liquid fuel from the device in the 10 event that the burners should accidentally become extinguished, or cease to burn, I provide an expansible rod, or wire 89, and pass it back over the burner, into the hot region produced thereby and secure it to a 15 support 90 which is attached to some fixed part, such as 91, of the device. I bring the wire forward and fix it to the end, as at 92, of a slidible rod 93, which is supported in bearings 94 and 95. A spring 96 serves to 20 hold the expansible rod 89 under tension and tends to pull it in a direction away from the support 90. The rod 93 is provided with a notch 97 near its front end. Pivoted in the shut-off device 22 is a valve 25 98, typically illustrated as a butterfly valve and shown to be open in Fig. 3. Secured to a stem 99, which passes through the fitting 22, is an arm 100 carrying a forwardly projecting stud 101 on its free end, which is 30 adapted to fit in the slot 97 of the rod 93. In Fig. 3 the valve is shown open. In Fig. 2 the valve is shown closed, which is its normal position when the device is not in operation.

35 The use and operation of the device is as follows:—The rod 93 is lifted so that the notch 97 clears the pin 101 and the arm 100 of the valve 98 is moved to the left, as shown in Fig. 3, thereby opening the valve and permitting liquid fuel to pass from the reservoir 12 through the pipe 20 into the needle valve structure 23 and from thence into the strainer 27 and into the pipe 31. Prior to 40 this time, however, a small amount of liquid fuel such as alcohol or the like, has been placed in the pan or box 34', of the casing shown in Fig. 5, and ignited, thereby to heat the liquid fuel that is then passing in the pipe 31 and to convert it into a gas 45 preliminarily to the complete operation of the device. After the gas is formed in the generator pipe 31 the burner 35' will supply the gas-generating heat and the device will operate as heretofore described. After the 50 burners have been lighted and the device is properly operating, the expansible bar 89 will become expanded and the spring 96 will pull the bar 89 and the rod 93 forwardly until the notch 97 drops over the pin 101 55 of the valve lever 100. Should the burners become extinguished for any cause other than shutting off the liquid fuel, then the expansible bar 89 will immediately contract and move the bar 93 against the resilient 60 effect of the spring 96 and since the notch

97 is now overlying the stud 101 of the lever 100 the contracting effect of the rod 89 will pull the arm 100 back into dotted line position shown in Fig. 3, thereby closing the valve. So long, however, as the 70 burner is supplying sufficient heat to maintain the expansible rod 89 sufficiently expanded the valve 98 will remain open. Should it be desired to close or to extinguish the burner at any time the rod 93 may 75 be lifted so that the notch 97 is clear of the stud 101 and the arm 100 may be moved back to dotted line position to close the valve 98 when in course of time the contraction of the heat responsive wire or rod 89 will again 80 bring the notch 97 in register with the stud 101 and the notch 97 will then permit the bar to drop over the stud 101 and hold the device with the valve 98 closed, so that it 85 cannot be accidentally opened by inadvertence or mistake.

Should, at any time the device become partly filled or clogged with deposits of carbon or the like, a detergent having the proper purging or solvent qualities may be 90 admitted into the pipe 20, as by the check-valve fitting 21, by inserting a pipe 103 in the check-valve portion 104 of the fitting 21 and by compressing the bulb 105 so as to 95 create a pressure within the detergent receptacle 106. The receptacle 106 may contain materials such as alcohol and potash or the like, which have the purging effect upon the deposits that usually accumulate within burners of this character. Other means 100 than that shown in Fig. 11 may be employed for this purpose, if desired, and other forms of shut offs embodying the features of my invention may be used and other changes in form and disposition of the many parts 105 within the scope of the appended claims may be made when desirable.

Having described my invention, what I claim is:—

1. In a device of the character described, 110 the combination of a casing comprising a box-like container having the box and cover fixed and spaced apart to provide a liquid container and a canopy; a generator tube, bent upon itself and contained within said 115 canopy; a burner within said box in a plane parallel with the general direction of the tube; a mixing chamber communicating with said generator tube, from which said burner is supplied, and a warm air conduit and a 120 regulable relatively cold air conduit communicating with said mixing chamber.

2. In combination, a mixing chamber, a fuel nozzle projecting into the chamber, a vapor tube in alinement with the nozzle and 125 extending outwardly from said chamber, an air inlet tube communicating with said chamber, a secondary mixing chamber connected with the outer end of the vapor tube, a fuel supply pipe connected with the nozzle, 130

a burner for heating the fuel supply pipe, and an independent burner for heating the secondary mixing chamber.

3. In combination, a mixing chamber, a fuel nozzle projecting into the chamber, a vapor tube in alinement with the nozzle and extending outwardly from said chamber, two air inlet tubes communicating with the said chamber on opposite sides thereof, a secondary mixing chamber connected with the outer end of said vapor tube, a fuel supply pipe connected with the nozzle, a burner for heating the fuel supply pipe, an inde-

pendent burner for heating the secondary mixing chamber, a regulable valve for the free end of one of the air tubes, the other of said air tubes intermediate its ends extending into close proximity to the last mentioned burner.

In testimony whereof I hereunto set my hand in the presence of two subscribing witnesses.

WILLIAM F. CATHCART.

In the presence of—
STANLEY W. COOK,
MARY F. ALLEN.
